CLOTHES WRINGERS

Frederick Roy Sibbald, Greenford, England, assignor to The Hoover Company, North Canton, Ohio, a corporation of Ohio

Application June 24, 1955, Serial No. 517,833

Claims priority, application Great Britain June 30, 1954

4 Claims. (Cl. 68—262)

This invention relates to clothes wringers and is particularly, but not exclusively applicable to power operated clothes wringers.

According to the present invention a wringer for clothes wherein the bearings for the upper and lower rollers are carried by frame members hinged together about an axis parallel to those of the rollers, the hinge pin being constituted by a torsion bar which also forms a spring to urge the frame member together to provide the operating pressure between the rollers.

Preferably the connection preventing or limiting relative turning between one frame member and the end of the torsion bar connected to it is releasable to permit free separation of the rollers and means may be provided for keeping the torsion bar stressed when the frame member is released from it. Thus in one arrangement one end of the torsion bar is anchored to one frame member whilst an arm projecting from its other end engages a stop carried by the same frame member, when released from the other frame member. The releasable frame member may carry a detent which can be projected or retracted to engage or clear the arm carried by the torsion bar. This detent conveniently has a cam surface so as to lift the arm from its stop and transfer the pressure to the rollers, even before they are forced apart by an appreciable thickness of clothes. The detent may be carried by a vertical shaft and from its projected position may be capable of being retracted by rotation of the shaft in either direction.

In one arrangement the anchored end of the torsion bar is secured to a stressing arm provided with means such as a screw for turning it relatively to the frame member to which it is connected, to stress the torsion bar.

The invention may be carried into practice in a number of ways, but one specific embodiment will be described by way of example with reference to the accompanying drawings, in which:

Figure 1 is a perspective view of the wringer in the open position with the operating lever in its operative position and the lower roller shown fragmentary, and in broken lines,

Figure 2 is a rear elevation, partly in section, of the wringer of Figure 1,

Figure 3 is a sectional side elevation on the line 3—3 of Figure 2, and

Figure 4 is a plan view of the wringer, partly in section, with the upper frame member and upper roller removed.

In the specific embodiment to be described, the invention is applied to a power wringer for a washing machine. The casing or frame of the wringer is afforded by a pair of frame members in the form of castings 10 and 11 of which the upper member 10 carries the bearings 12 and 13 for an upper wringer roller 14, while the lower frame member 11 carries the bearing 15 for one end of a lower roller 16, and the bearing 17 for a driving stub shaft 18. The lower frame member is provided with drain holes 23.

The upper roller 14 is securely fixed in position in the

2

upper frame member by U-shaped brackets which form the lower halves of the bearings 12 and 13. The lower roller 16, however, is loosely mounted, the bearing 15 being of open form. As shown in Figure 4, the stub shaft 18 has a pair of driving dogs 19 which engage a co-operating slot 20 in the end of the lower roller shaft. For power operation, drive is transmitted to the lower roller through a worm gear 21 mounted in a gear casing 22 integral with and at one end of the lower frame member.

The two frame members are hinged together about an axis parallel to those of the rollers by means of a torsion bar 25 passing through a pair of lugs 26 formed on the upper frame member and a pair of lugs 27 formed on the lower frame member. The centre portion of the torsion bar is bowed upwards slightly in order that the clothes can clear it as they pass through the wringer.

One end 29 of the torsion bar is bent at right angles to form an operating arm whilst the other, anchored, end 30 of the torsion bar is of increased diameter and is provided with a key 31. This end of the torsion bar fits into what may be termed a stressing arm 32 having a slot to receive the key 31 to prevent relative rotation between the arm and the end of the torsion bar. The end of the increased diameter portion is grooved to receive a retaining ring or circlip 33 by which the torsion bar is held against longitudinal movement. As shown in Figure 1 the free end of the stressing arm 32 is forked at 34 and an adjusting bolt 35 passes between the limbs of the fork and is threaded into the lower fixed frame member 11.

The parts are so formed that when the torsion bar is unstressed with its operating arm 29 resting on a raised stop 36 on the lower frame member, the stressing arm 32 will be at some distance from the surface of the frame member into which the adjusting screw fits. Accordingly by tightening the adjusting bolt 35 and pulling the stressing arm 32 down towards the frame member the torsion bar can be pre-stressed. As shown in Figure 3 the extent to which a particular wringer may have its torsion bar stressed is governed by the thickness of a spacing sleeve 37 lying between the frame member and the stressing arm.

Extending vertically through a bore in the upper frame member, adjacent the operating arm 29 of the torsion bar, is a locking shaft 40 carrying at its lower end a detent in the form of a foot 41, which can be turned with the shaft so as either to extend underneath the operating arm 29 of the torsion bar or to be retracted clear of it. As is clearly shown in Figure 2, the upper surface of the foot 41 is inclined to form a cam surface 43 so that as the shaft is turned to engage the foot with the operating arm, the latter is lifted slightly so as to transfer the pressure from the stop 36 to the upper frame member and hence to the rollers.

At its upper end the locking shaft 40 carries an operating lever 42 projecting forwards, i. e. towards the user, for easy manual operation. It will be appreciated that the rollers can be released by moving this lever either to the left or to the right from the locked position. A spring 45 is provided which surrounds the torsion bar 30, one end 46 of the spring bearing on a reinforcement rib 47 of the upper frame member, whilst the other end bears on the inside of the lower frame member as shown in Figure 3. In this way the two frame members are biased away from one another and accordingly when the operating lever is moved away from the locked position the frame members and the rollers are immediately separated. The spring 45 will of course be very much weaker than the torsion bar, so as not to interfere with the action of the latter in pressing the rollers together.

The gear casing 22 is provided with a spigot 44 to

engage a socket carried by a washing machine for mounting the wringer on the washing machine, and the wringer may have alternative operating positions in different angular relationship to the washing machine, so that in one position rotation in a given direction will wring the clothes away from the washing machine container, whilst in another position it will wring them towards it.

It will be appreciated that the construction described provides a simple arrangement whereby the same member, namely the torsion bar, provides the hinge between the frame member, and also the spring which biases them and the rollers together.

When large articles are fed through the wringer, the rollers and the frame are separated against the action of the torsion bar. In order to overcome any risk of clothes or the operator's fingers being pinched between the frames when they return to the normal position, guards 48 are provided at each end which cover the space between the frames.

What I claim and desire to secure by Letters Patent is:

1. A clothes wringer comprising a pair of frame members, a pair of rollers, one in each of said frame members, a torsion bar spring forming a hinged connection between said frame members for relative movement of the latter and corresponding relative movement of said rollers, said torsion bar being unitary for the length of said rollers and having an end fixed to one of said frame members and the other end movable, and latch means on the other frame member mounted for movement to one position into engagement with said movable end of said torsion bar to transfer the torsion bar pressure to said rollers by relative movement of the latter.

about said torsion bar hinge, and said latch means movable to a second position out of engagement with said movable end to release said other frame member and said rollers from the force of said torsion bar and permit relative movement of said frame members about said torsion bar hinge.

2. A clothes wringer as described in claim 1, and stop means arranged with respect to said one frame member engageable with said movable end of said torsion bar when released from said latch means to position said movable end for reengagement with said latch means upon movement of the latter to said one position to transfer the torsion bar pressure to said rollers.

3. A clothes wringer as described in claim 1, and said latch means including cam means engageable with said movable end of said torsion bar to rotate the latter and increase the pressure transferred to said rollers during movement of said latch means to its said one position.

4. A clothes wringer as described in claim 1, and stress means at all times securing said fixed end of said torsion bar to said one frame member and including means to adjust the pressure exerted by said torsion bar on said rollers.
